2 SHEETS—SHEET 2.

UNITED STATES PATENT OFFICE.

STEPHEN O. HEINDL, OF CHICAGO, ILLINOIS, ASSIGNOR OF ONE-HALF TO ERNEST ZEITZ, OF CHICAGO, ILLINOIS.

SCISSORS-GRINDING MACHINE.

1,427,735.

Specification of Letters Patent. Patented Aug. 29, 1922.

Application filed September 24, 1921. Serial No. 503,029.

To all whom it may concern:

Be it known that I, STEPHEN O. HEINDL, a former subject of the Emperor of Austria (who has declared his intention of becoming an American citizen), residing at Chicago, in the county of Cook and State of Illinois, have invented certain new and useful Improvements in Scissors-Grinding Machines, of which the following is a specification.

The invention relates to a machine for grinding scissors and the like, the aim being to enable an unskilled operator to sharpen the scissors effectively with a minimum expenditure of time and effort.

With this aim in view, the primary object of the invention is to provide a machine which is substantially automatic in operation, it being only necessary to adjust the scissors blade to the grinding wheel and apply power to the driven element.

A further object of the invention is to provide improved means for releasing the carriage upon which the scissors are clamped, from the feeding mechanism.

Still another object of the invention is to provide an improved means for supporting the scissors to be ground which is capable of adjustment to vary the angle at which the blade is held to the grinding wheel, whereby to enable the operator to obtain any desired bevel on the cutting edge.

A general object of the invention is to provide a machine of an exceedingly practical character, which may be manufactured at a relatively low cost, which is durable, and which presents a neat appearance.

The objects of the invention thus set forth, together with other and ancillary advantages, are obtained by the construction and arrangement illustrated in the accompanying drawings forming part hereof, but it is contemplated that various changes in form, construction and arrangement may be made by those skilled in the art without departing from the spirit and scope of the invention as expressed in the appended claims.

In Figure 1 of the drawings I have illustrated my improved machine, the figure being a central, vertical sectional view. Fig. 2 is a plan view of the machine. Fig. 3 is a vertical sectional view through the work clamp. Fig. 4 is a fragmentary, vertical, sectional view taken in the plane of line

4—4 of Fig. 2 and illustrating the carriage releasing means. Fig. 5 is a sectional view taken on the line 5—5 of Fig. 4.

The machine comprises a base or frame 7 having mounted therein a horizontal shaft 8 constituting a combined feed screw and operating shaft. 9 designates generally the carriage which is operatively connected with the feed screw and slides upon two longitudinal rods 10. 11 indicates the work clamp mounted upon the carriage, and 12 the grinding wheel operatively connected with the shaft 8 and mounted for rotation on an axis above and parallel to the shaft 8 with its periphery disposed in the path of movement of the scissors secured in the work clamp 11.

The frame 7 comprises a base plate 13 having at its opposite ends a pair of uprights or standards 14 and 15. These standards are preferably formed integral with the base plate and they are respectively provided with journal bearings 16 and 17 for the opposite ends of the shaft 8. The forward end of the shaft projects through its bearing 16 and has secured thereon a relatively heavy hand wheel 18. For supporting the rods 10, the standard 14 has secured thereto, as by means of a bolt 19, a V-shaped bracket 14^a having a pair of upwardly extending arms disposed upon opposite sides of the journal bearing 16. The forward ends of the rods 10 are mounted in these arms, and the opposite ends of the rods are entered in suitable apertures in the standard 15.

The carriage 9 comprises a lower or base portion in the form of a yoke 20 having formed at its opposite ends sleeves 21 and 21^a slidably mounted upon the rods 10. 95 Rising from the central portion of the yoke is a stem 22 carrying a transverse bearing 23 for a supporting rod 24 of the work support. The bearing 23 is provided with a thumb screw 25 projecting forwardly from the bearing and adapted to clamp the rod in any desired position of lateral adjustment.

The carriage 9 has an operative connection with the shaft 8, in the form of a segmental nut 26 adapted to engage the threads 105 of the shaft 8. The nut 26 is carried by a lever 27 mounted between its ends upon one of the rods 10 and inserted in a slot 28 cut transversely through the sleeve 21. A coiled expansion spring 29 is entered at one 110

end in a socket 30 provided in the under side of the yoke 20 and bears at its other end upon the upper surface of the segmental nut 26. The spring thus acts to maintain 5 the nut normally in engagement with the shaft 8. The lever 27 projects radially outwardly from the sleeve 21, to form a thumb piece 31 whereby the nut 26 may be swung against the action of the spring 29 10 out of engagement with the screw shaft 8. By this means the carriage may be disassociated from the shaft and slid longitudinally of the machine as may be desired.

The spring 29 is preferably made of substantial strength so as to maintain effectively the nut 26 in engagement with the shaft 8. In order therefore to facilitate the operation of sliding the carriage free of the shaft, I provide a spring-actuated detent, 15 shown particularly in Fig. 4. This device comprises a plunger 32 slideable within a bore 33 provided in a downward extension 34 of the sleeve 21. A coiled expansion spring 35 encircles the plunger 32 and acts 20 between a bushing 36 closing the outer end of the bore and a collar 37 fixed on the plunger. The inner or rear end of the plunger normally engages with the forward face of a dependent portion 38 of the lever 27, and when the lever is swung to carry the segment 26 out of engagement with the shaft 8, the plunger is forced by the spring 35 into a socket 39 in the forward face of the dependent portion 38, said socket being arranged 25 so as to be in direct alinement with the plunger when the segment 26 is in its inoperative position. By this means, it will be apparent, the lever may be yieldably locked in position to hold the segmental nut 30 disassociated from the screw shaft 8.

The work-clamp supporting means comprises a bearing 40 formed rigid with the rod 24, which it will be remembered is adjustably mounted in the bearing 23 upon the carriage. A rod or stem 41 carrying a head 42 is entered through the bearing 40, and a thumb screw 43 screw threaded upon the free end of the stem 41 is adapted to clamp the head in any desired position of adjustment on an axis parallel to the axis of the grinding wheel. The head 42 is bored vertically thereof to receive the stem 44 of the clamp in which the scissors to be ground are secured.

55 This clamp comprises a lower or stationary jaw 45 fixed upon the stem 44 and an upper jaw 46 slideable on the stem. Said upper jaw is normally held spaced from the lower jaw by means of a coiled expansion spring 47, but is held against relative rotary movement by a pin 48 rigid therewith and engaging in an aperture 49 formed in the lower jaw. The latter is secured to the stem 44 by means of a pin 50. To receive the lower end of the spring 47, the

lower jaw is provided with a socket 51 in its upper surface, of a size adapted to completely house the spring when the jaws are clamped together. A thumb-screw 52 upon the upper end of the stem 44 is provided 70 for this purpose. 53 designates a socket in the adjacent faces of each of the jaws 45 and 46 for receiving the head and nut of the connecting bolt for the blades of the scissors. Preferably the faces of the jaws are 75 cut away at the forward edges of the sockets as at 54 to receive the head and nut of said connecting bolt.

In order that the blade of the scissors being ground shall be held automatically to 80 the grinding wheel, I provide means comprising a coiled torsion spring 55 entered within a socket 56 in a sleeve 57 secured upon the lower end of the stem 44, which latter projects a short distance below the bearing 42. The sleeve is secured in position upon the stem by means of a set screw 58. The spring is thus arranged to encircle the lower end of the stem, and its lower end 59 is inserted into a hole at the bottom of the 90 socket 56 and its upper end 60 is entered into a hole drilled in the lower end of the bearing 42. The arrangement is such that the spring 55 tends to rotate the stem 44 and hence the work clamp in a direction to carry 95 the blade being ground toward the grinding wheel. Preferably means is provided to limit the rotation of the work clamp under the action of the spring 55. This means herein comprises a pin 61 projecting radially 100 from the stem 44 and engaging with a shoulder 62 formed by cutting away a portion of the upper end of the bearing 42.

The grinding wheel 12 (Fig. 1) is mounted near the upper end of the standard 15 105 upon a stud shaft 63, the standard being provided with a forwardly projecting journal bearing 64. This standard it will be observed is made hollow to form a chamber 65 for enclosing the gearing constituting 110 the connection between the grinding wheel shaft and the driven shaft 8. The rear wall of this chamber is formed by a plate 66 detachably secured to the standard as by means of screws 67. This plate is provided near 115 its upper end with a journal bearing 68 having a bushing 69 of suitable metal in which the rear end of the wheel shaft 63 operates; and near its center has a forwardly projecting stud 66^a against which the rear end 120 of the shaft 8 is adapted to abut. A nut 70 is provided on the rear end of the shaft 63; and preferably a fiber washer 71 is interposed between the nut and the rear face of the journal bearing 68. A stop screw 72 is 125 entered through the nut 70 so as to engage the rear end of the shaft 63. By this means it will be apparent the parts may be nicely adjusted so as to operate smoothly and noiselessly.

Fixed upon the grinding wheel shaft 63 is a pinion 73 meshing with a spur gear 74 fast upon the rear end of the main shaft 8. The rotation of said shaft through the application of power to the hand wheel 18 thus effects a rotation of the grinding wheel through gearing 74, 73, and the feeding of the carriage toward or from the grinding wheel. Preferably the rearward movement of the carriage is limited by one or more stops 75 adjustably secured upon the rods 10.

In the use of the machine, the scissors are inserted between the jaws 45, 46 of the work clamp while the carriage is near the forward end of its travel. The carriage is now moved rearwardly toward the grinding wheel to carry the blade to be ground opposite the wheel, and then by manipulating the thumb screws 25, 43 and 52 the blade is positioned at the desired degree of angularity with reference to the surface of the grinding wheel and at the proper distance from the grinding wheel so that the spring 55 exerts a slight pressure of the blade upon the grinding wheel. The carriage is now positioned so that the rear ends of the sleeves 21 and 21^a engage with the collars 75 fixed upon the rods 10, these collars having been set so that the rear end of the cutting edge of the blade is positioned adjacent the forward edge of the grinding wheel.

Power is now applied to the shaft 8 through the operation of the hand wheel 18, the wheel being turned in a clockwise direction. The grinding wheel is thus caused to rotate in the opposite direction away from the cutting edge of the blade, and simultaneously the carriage is fed forwardly by the action of the screw threads engaging the segment 26 of the carriage.

If one operation or stroke of the blade across the grinding wheel is not sufficient, the carriage is returned to its rearmost position for another operation. This is accomplished by depressing the thumb piece 31 of the lever 27 until the detent 32 engages in the socket 39 in the depending portion 38 of said lever. The segmental nut 26 is now held out of operative engagement with the screw shaft 8 and the carriage is free to slide upon the rods 10 independently of the shaft 8. Such release of the carriage is advantageous in that it enables the operator to return the carriage to its initial position quickly and with a minimum expenditure of effort; and the means for locking the segmental nut in its inoperative position insures that it will not be permitted to engage with the shaft in its sliding movement.

Preferably this nut is formed of brass or similar material and since the spring 29 is necessarily made of substantial strength, in order to hold the nut in its operative position, the positive locking of the nut in its

raised position insures that a careless operator will not be able to allow the nut to engage in the threads, in the sliding movement of the carriage, to the injury of the threads of the nut.

It will be seen that I have provided a machine which is substantially automatic in operation, it being only necessary to initially adjust the work and apply power to the driven shaft. The work is firmly held in its clamp, and maintained yieldingly in contact with the grinding wheel. A bevel of any desired degree may be secured by a simple adjustment of the clamp support, and the work itself may be readily fastened in the clamp, adjusted with reference thereto, and removed therefrom. Furthermore, the construction provided is exceedingly practical, being relatively simple so that it may be manufactured at a low cost.

I claim as my invention:

1. In a grinding machine, the combination with a rotatable grinding element, of means for moving the work transversely of said element comprising a traveling carriage, a work clamp mounted on said carriage comprising an oscillatory stem, a pair of jaws held against rotation on said stem, and spring means acting upon said stem to rotate it in a direction to carry the work toward the periphery of the grinding wheel.

2. In a grinding machine, the combination with a grinding wheel, of means for supporting the work for the grinding operation comprising a stationary head, a stem mounted to rotate in said head, means carried by said stem for clamping the work, and means acting between the stem and said head for rotating the stem in a direction to hold the work to the wheel.

3. In a grinding machine, the combination with a grinding wheel, of means for supporting the work for the grinding operation comprising a stationary head, a stem mounted to rotate in said head, means carried by said stem for clamping the work, means acting between the stem and said head for rotating the stem in a direction to hold the work yieldingly to the wheel, and means for limiting the rotation of the stem by the last mentioned means.

4. In a grinding machine, a work supporting means comprising, in combination, a laterally adjustable rod, a bearing on the end of said rod, a head having a stem entered through said bearing so as to be adjustably secured therein, and a work clamp having a stem mounted in said head in perpendicular relation to the first mentioned stem.

5. In a grinding machine of the class described, the combination of a grinding wheel, a carriage movable in a direction parallel to the axis of said wheel, and work supporting means on said carriage comprising a stem, means on said carriage for sup-

- porting said stem for adjustment on a horizontal axis, and a clamp carried by said stem.
6. In a grinding machine, the combination with a rotatable grinding wheel, a carriage mounted for movement in a direction parallel to the axis of said wheel, and work-holding means mounted for rotative adjustment on an axis also parallel to the axis of said grinding wheel.
7. In a grinding machine, the combination with a rotatable grinding wheel, a carriage mounted for movement in a direction parallel to the axis of said wheel, and work-holding means mounted for rotative adjustment on an axis also parallel to the axis of said grinding wheel and for lateral adjustment transversely of said axle.
8. In a grinding machine, the combination with a rotatable grinding wheel of a carriage movable in a direction parallel to the axis of said wheel, means adjustable transversely of said axis for supporting the work, a work clamp carried by the last mentioned means rotatable upon an upright axis, and spring means for rotating said clamp on its axis whereby to carry the work against the grinding wheel.
9. In a grinding machine, the combination with a rotatable grinding wheel of a carriage movable in a direction parallel to the axis of said wheel, means for supporting the work adjustable on an axis also parallel to the axis of the wheel, a work clamp carried by the last mentioned means rotatable upon an upright axis, and spring means for rotating said clamp on its axis whereby to
- carry the work against the grinding wheel.
10. In a grinding machine, the combination with a rotatable grinding wheel of a carriage movable in a direction parallel to the axis of said wheel, means for supporting the work adjustable transversely of said axis and also on an axis parallel to the axis of the wheel, a work clamp carried by the last mentioned means rotatable upon an upright axis, and spring means for rotating said clamp on its axis whereby to carry the work against the grinding wheel.
11. In a grinding machine, a feed screw, a carriage, a lever on said carriage having a nut normally engaging said screw, and means for locking said lever in position to hold the nut in its inoperative position, said means comprising a spring actuated detent carried by the carriage, and a part on said lever having a socket adapted to receive said detent when the nut is in its inoperative position.
12. In a grinding machine, the combination of a frame, a standard at each end of the frame, a carriage, a feed screw for said carriage mounted at its opposite ends in said standards, a V-bracket carried by one of the standards having its upper ends disposed upon opposite sides of the standard, and a pair of slide rods mounted at one end in the upper ends of said bracket and at their opposite ends in the other one of said standards.

In testimony whereof, I have hereunto set my hand.

STEPHEN O. HEINDL.
